PLOTTING INSTRUMENT

Albert J. Kramer, Arlington, Va., assignor to
 Claude R. Wickard, as Secretary of Agriculture
 of the United States of America, and his suc-
 cessors in office

Application April 2, 1943, Serial No. 481,560

4 Claims. (Cl. 33—20)

(Granted under the act of March 3, 1883, as
 amended April 30, 1928; 370 O. G. 757)

This application is made under the act of March 3, 1883, as amended by the the act of April 30, 1928, and the invention herein described, if patented, may be manufactured and used by or for the Government of the United States of America for governmental purposes without the payment to me of any royalty thereon.

This invention relates to plotting instruments of the same general character as those disclosed in the patent to Wernstedt, No. 2,303,099, granted November 24, 1942, and in the copending application of Flynn and Kramer, Serial No. 478,644, filed March 10, 1943; and has among its objects improvements in plotting instruments, particularly relative to improving the means for carrying the tracing point in such manner that maps can be reproduced on an enlarged or a reduced scale, and such other objects as will be apparent from the following description and claims and the annexed drawings, in which:

Figure 1 is a front elevation of the plotting instrument;

Figure 2 is a section on the line 2—2 of Figure 3;

Figure 3 is a side elevation of the instrument;

Figure 4 is a fragmentary section on the line 4—4 of Figure 1; and

Figure 5 is a section on the line 5—5 of Figure 2.

Referring to the drawings with more particularity, the embodiment illustrated is provided with a base 11, suitably supported on adjustable leveling rests 12. Frame members 13 and 14, shaped to provide uprights 15 and 16 and horizontal arms 17 and 18, respectively, are suitably secured to the rear of the base with the horizontal arms extending forwardly thereabove. Transverse parallel front and rear bars 19 and 20 extend across the forward ends of the horizontal arms and are secured thereto by set screws 21 in the manner illustrated.

A unit 22, forming part of a stereoscope and having eye pieces 23 and 24 and eye mirrors 25 and 26, is carried by bracket 27 which, in turn, is carried on another bracket 28. The latter bracket is adjustably mounted on the front bar 19 with a tight sliding fit, and has a rearwardly extending projection 29 positioned beneath the rear bar 20. A wing screw 30, threaded through the projection 29 and engaging the bar 20, provides for adjusting the position of the unit 22 vertically. The unit 22 is adjustable on horizontal pivot bolt 31 by manipulation of screws 32 and 33, which are threaded through projections on bracket 27 and bear on an abutment 34 fixed to the stereoscope unit 22, and is adjustable on vertical pivot bolt 35 by manipulation of similar

screws, one of which is shown at 36, which are threaded through other projections on bracket 27 and bear on a stationary abutment 37 fixed to the bracket 28.

5 Stereoscope wing mirrors 38 and 39 are carried by brackets 40 and 41, which are also slidably mounted on bars 19 and 20 and are made adjustable by means similar to the means for adjusting the unit 22.

Phototables 42 and 43 for supporting the stereoscopic pictures are suitably mounted on the front of the base 11. The manner of supporting and adjusting the tables is substantially the same as that described in the above-mentioned patent, to 15 which reference is made for a complete description thereof.

Frames 51 and 52, carrying index mark disks with the index marks movable in three coordinate directions in the field of vision of the stereoscope, 20 are mounted on horizontal bar 53, which in turn is mounted for vertical movement on racked vertical columns in the form of tubes 54 and 55, and is operated by a hand wheel 56 driving a shaft 57 to which pinions, one of which is shown at 58, are attached and meshed with the racked tubes. A graduated scale wheel 59 is movable with the hand wheel, and its setting is indicated by index pointer 60.

The bar 53 and parts carried with it are counter-balanced by weights one of which is shown at 61 disposed inside the vertical tubes 54 and 55, respectively. The counterweights are suitably connected to the bar by flexible cables 62 and 63, which are attached at their free ends to the counter-balanced parts, and are belted over pulleys 64 and 65 attached at the top of the tubes to hinge knuckles 89 and 90.

Frames 51 and 52 are made adjustable relative to each other. Frame 51, for example, is adjustable vertically and horizontally by manipulation of screws 66 and 67 the first of which is journaled in a bracket 68, which is slidable on bar 53, and is threaded through the frame. Screw 67 is journaled in a bracket 69, which is fixed on bar 53, and is threaded through bracket 68. The frame 51 is guided in its vertical movement by guides 70 secured to bracket 68 and slidably fitted in apertures extending through the frame.

A horizontal rod 71 is attached at its ends to the lower ends of tubes 54 and 55.

The parts heretofore described, although improved in structure, are substantially the same in their general function as the corresponding parts of the patent to which reference is made above.

The means for movably supporting the parts

carrying the index marks is, however, different from the corresponding means of the patent. This means, as shown most clearly in Figure 2, comprises a linkage of rigid members, or sides, forming at least two parallelograms with a common side, with the side of the first parallelogram opposite the common side fixed against movement, and with all corners hinged, allowing freedom of movement in all horizontal directions of the unfixed side of the second parallelogram which is opposite the common side and which forms a carriage for the index marks.

The first parallelogram has as its fixed side the base 11 to which the uprights 15 and 16 are fixedly secured. Sides 80 and 81, which are of equal length, are hinged at their ends to the uprights on pintle pins 82 and 83, respectively, and at their opposite ends to the ends of the common side 84, which is of length equal to the distance between the hinges on the uprights, on pintle pins 85 and 86. The second parallelogram has its sides 87 and 88, which are of equal length, hinged at their ends on pintle pins 85 and 86, and at their opposite ends on the movable side, or carriage, which is also of length equal to the distance between the hinges on the uprights and which comprises horizontal bar 53, rod 71 and tubes 54 and 55. The tubes are journaled at their ends in hinge knuckles 89, 90, 91 and 92, integrally attached to the ends of the sides 87 and 88. For ease in movement, the pintle pins may be fixed in reference to one of the sides and frictionless bearings (not shown) provided at the bearing points.

From the structure disclosed, it will be observed that the index marks are carried by the movable side of the linkage and will always remain in the same position relative to each other, except for adjustments and vertical displacements; and that the linkage is supported solely by the frame and the index marks are constrained to move in traversing the stereoscopic pictures so that every position of the marks is parallel to every other position.

The parallelism linkage above described is essentially the same as that described and claimed in the copending application of Flynn and Kramer, mentioned above.

The improvement in this application over the copending application relates to the means for carrying a tracing point which provides for drawing maps on enlarged or reduced scales, the principles of which means are most clearly illustrated in Figure 2.

The means for making enlarged maps comprises an enlarging linkage system, shown at the left of Figure 2, attached to the parallelism linkage and carrying the tracing point. The linkage system is provided by a link 100 fixed to the side 80 and equal to it in length. In the particular embodiment shown, link 100 is formed as an integral extension of lower member 101 of the side 80. A link 102, twice as long as link 100, is attached at its one end to the free end of link 100 with a hinge joint, and carries the tracing point 103 at its other end. Link 104, of length equal to link 100, is attached at one of its ends to the midpoint of link 102 with a hinge joint and at its other end to the corner of the parallelogram at the end of side 87. A map table 105 is supported on the base 11 under the tracing point.

Tracing point 103 is spring-pressed downwardly and when not in use may be raised and held elevated by an upward lift and rotation of thumb grip 106.

The tracing point will traverse a figure similar and of double scale to any figure traversed by the index marks.

If it is desired to reproduce a figure on reduced scale the reducing linkage system shown at the right of Figure 2 may be employed. The two systems may, if desired, be used concurrently for the purpose of simultaneously making more than one map.

The reducing linkage system is provided by a pair of links 107 and 108 connected together at their ends with a hinge joint and arranged to be adjustably connected with hinge joints at their other ends to sides 81 and 88, respectively, of the parallelism linkage. The adjustability, which provides means for varying the scale of reduction, is provided by a series of apertures 109 and 110 in the lower members 111 and 112 of the sides 81 and 88, respectively, and another series of apertures in links 107 and 108 to be selectively mated with the first-mentioned series of apertures and held in position by bolts 113 and wing nuts 114 and 115, in the manner illustrated. The series of apertures are so positioned that the links 107 and 108 and members 111 and 112 form a parallelogram, for different reduced scale adjustments. A tracing point 116, similar to tracing point 103, is carried at the hinge point of links 107 and 108, and a map table 117 is supported on base 11 beneath the tracing point 116. Smaller scale figures are produced when the adjustment of links 107 and 108 provides the smaller parallelogram.

From the above, it will be understood that this invention combines a parallelism linkage with a pantograph, the parallelism linkage being disposed between the usual fixed point (82 in the case of the enlarging pantograph and 83 in the case of the reducing pantograph) and scanning point (89 in case of the enlarging pantograph and 80 in case of the reducing pantograph) of the pantograph. The enlarging pantograph, as shown in the drawings, has an extended link and another link, connecting its fixed and scanning points, in common with sides 89 and 87, respectively, whereby its fixed and scanning points coincide with hinge joints of the fixed and movable sides of the parallelism linkage at one end. Similarly, the reducing pantograph has links connecting its fixed and scanning points in common with sides 81 and 88, whereby its fixed and scanning points coincide with the hinge joints of the fixed and movable sides of the parallelism linkage at the other end.

It is to be understood that additional pantographs may be combined in series with either the enlarging or reducing pantograph to obtain different scales of enlargement and reduction without departing from the spirit of this invention, such combinations being well known in the art.

Having thus described my invention, I claim:

1. A plotting instrument comprising a parallelism linkage provided by rigid members forming two parallelograms having a common side and having all sides connected at the corners of the parallelograms with hinge joints, the side of one parallelogram opposite the common side being fixed against movement, the corresponding side of the other parallelogram being movable; in combination with an enlarging pantograph and a reducing pantograph, each pantograph having a fixed point, a scanning point, and a tracing point, the fixed points of the pantographs being coincident with the two hinge joints of the

fixed sides of the parallelism linkage, respectively, and the scanning points being rigidly connected to the movable side.

2. In a plotting instrument of the character described, a frame, a stereoscope supported by the frame and index marks movable in the field of vision of the stereoscope, said index marks being carried by a parallelism linkage provided by rigid members forming two parallelograms having a common side and having all sides connected at the corners of the parallelograms with hinge joints, the side of one parallelogram opposite the common side being fixed against movement relative to the frame, the corresponding side of the other parallelogram being movable, the index marks being carried by the movable side, whereby they are constrained to move in traversing a stereoscopic picture so that every position of the marks is parallel to every other position; in combination with an enlarging pantograph and a reducing pantograph, each pantograph having a fixed point, a scanning point, and a tracing point, the fixed points of the pantographs being coincident with the two hinge joints of the fixed side of the parallelism linkage, respectively, and the scanning points being rigidly connected to the movable side, whereby for any figure traversed by the index marks the tracing points of the pantographs will traverse similar enlarged and reduced figures.

3. A plotting instrument comprising a parallelism linkage provided by rigid members forming two parallelograms having a common side and having all sides connected at the corners of the parallelograms with hinge joints, the side of the parallelogram opposite the common side being fixed against movement, the corresponding side of the other parallelogram being movable; in combination with an enlarging pantograph

having an extended link in common with the side of one of the parallelograms adjacent the fixed side, whereby the fixed point of the pantograph coincides with the hinge joint at the end 5 of the fixed side, a link in common with the side of the other parallelogram adjacent the movable side, whereby the scanning point of the pantograph coincides with the hinge joint of the movable side, a link rigidly connected to the extended link, a link hinged at one end to the end 10 of the rigidly connected link and carrying a tracing point at its other end, and a link connecting the scanning point of the pantograph to the central portion of the link carrying the tracing point.

4. A plotting instrument comprising a parallelism linkage provided by rigid members forming two parallelograms having a common side and having all sides connected at the corners of 15 the parallelograms with hinge joints, the side of the parallelogram opposite the common side being fixed against movement, the corresponding side of the other parallelogram being movable; in combination with a reducing pantograph having two links in common with the two sides of the parallelism linkage adjacent the common side, whereby the fixed and scanning points of the pantograph coincide with the hinge joints at 20 the end of the fixed side and of the movable side, respectively, and two links connected together with a hinge joint and carrying a tracing point coincident with the hinge joint, said last-mentioned two links being adjustably connected with hinge joints to the first-mentioned two links, whereby for any figure traversed by the 25 scanning point, the tracing point may be made to traverse a similar figure of a reduced variable scale.

ALBERT J. KRAMER.
